(57) **CLAIM**

The ornamental design for a combined mounting and junction box, as shown and described.

DESCRIPTION

FIG. 1 is a bottom perspective view of a combined mounting and junction box in accordance with the present invention. FIG. 2 is a rear perspective view showing the combined mounting and junction box of FIG. 1.

FIG. 3 is a front elevation view showing the combined mounting and junction box of FIG. 1.

FIG. 4 is a rear elevation view showing the combined mounting and junction box of FIG. 1.

FIG. 5 is a left elevation view showing the combined mounting and junction box of FIG. 1.

FIG. 6 is a right elevation view showing the combined mounting and junction box of FIG. 1.

FIG. 7 is a top plan view showing the combined mounting and junction box of FIG. 1.

FIG. 8 is a bottom plan view showing the combined mounting and junction box of FIG. 1.

FIG. 9 is an exploded top perspective view, with the lid separated, showing the claimed design of FIG. 1; and, FIG. 10 is a top perspective view of FIG. 1, and shown in an environment.

In the drawings, the broken lines are for the purpose of illustrating portions of the combined mounting and junction box that form no part of the claimed design. In FIG. 10 the broken lines are for the purpose of illustrating portions of the article not a part of the claimed design and environment that form no part of the claimed design.

1 Claim, 5 Drawing Sheets
